(57) **CLAIM**

The ornamental design for a compact utility knife incorporating a bottle opener and keychain attachment, as shown and described.

DESCRIPTION

FIG. 1 is a top perspective view of a compact utility knife incorporating a bottle opener and keychain attachment showing my new design, wherein the blade lock is in the open position;

FIG. 2 is a front elevation view of FIG. 1,

FIG. 3 is a front elevation view thereof, where in the lock is

in the closed position;

FIG. 4 is another front elevation view like FIG. 3 but with the broken line showing of the blade omitted,

FIG. 5 is a rear elevation view thereof, wherein the lock is in the closed position;

FIG. 6 is a top plan view thereof;

FIG. 7 is a bottom plan view thereof;

FIG. 8 is a left elevation view thereof;

FIG. 9 is a right elevation view thereof; and,

FIG. 10 is an environmental drawing showing the utility knife opening a bottle with the bottle opener.

The broken lines showing a blade, bottle and bottle cap depict environmental subject matter only and form no part of the claimed design.
